UNITED STATES PATENT OFFICE.

EDWARD L. HUNTSMAN, OF ROCHESTER, TEXAS.

COTTON-GIN.

1,229,084.

Specification of Letters Patent. Patented June 5, 1917.

Application filed June 19, 1916. Serial No. 104,541.

To all whom it may concern:

Be it known that I, EDWARD L. HUNTSMAN, a citizen of the United States, residing at Rochester, in the county of Haskell 5 and State of Texas, have invented certain useful Improvements in Cotton-Gins, of which the following is a specification, reference being had therein to the accompanying drawing.

10 This invention relates to improvements in cotton gins, one object of the invention being the provision of an attachment for a gin feeder to separate cotton from the burs during the gin operation, the same 15 being especially adapted for use upon cotton containing an excess amount of bolls.

A further object of the present invention is the provision of an air suction device whereby the cotton will be removed from 20 the burs before its entrance into the gin instead of carrying to the huller breast the cotton and burs together.

A still further object of this invention is the provision of a simple and comparatively inexpensive mechanism which is 25 adapted to dispense with the cotton sliding board used in cleaner feeders for cotton and which will operate to separate the cotton from the burs or bolls before the entrance thereof upon the gin stand or huller breast.

In the accompanying drawings;—

Figure 1 is a side elevation of a cleaner feeder with the present attachment in use, 35 such attachment being shown in section to illustrate the various positions of the parts.

Fig. 2 is a top plan view thereof.

Fig. 3 is a view on an enlarged scale 40 of the present attachment showing by arrows and spears the directions of travel of the cotton and burs.

Figs. 4 and 5 are detailed views of various parts.

Referring to the drawings, the numeral 45 10 designates the cleaner feeder mechanism which is of any preferred form, the present separating attachment 11 being introduced in lieu of the usual cotton sliding board applied in connection with a cleaner feeder.

50 This attachment consists of a casing 12 which has mounted therein a slanting partition 12' for dividing the casing into an upper compartment and a lower compartment in the latter of which is mounted for

rotation a saw cylinder 13 which is preferably eight inches in diameter, coarse teeth preferably six to the inch. Disposed throughout the width of the opening 14 in the partition which establishes communication between the upper and lower compartments are the ribs 15, while extending from each side of the casing 12 is a suction pipe 16 which leads to the reduced four-inch flue 17. Thus, a suction of air through the pipe also passes through the ribs and 60 draws the cotton so that it will adhere to the cylinder 13 to be pulled off the saw by the suction and to lodge against the perforated plate 18.

The roller 19 is substantially six inches 70 in diameter and is provided with the elastic or rubber belt flaps 20 which serve to direct the action of the suction to the top of the cylinder and which clean the cotton from the perforated plate and direct it 75 down the lower compartment which is arranged in communication with the top of the cotton roll chamber 21' of the gin stand 22.

An arcuate shield 21 extends from the partition 14 and is positioned beneath the cylinder 13 terminating short of the roller 19 so as to prevent the action of the suction of air on the under surface of the cylinder.

A slatted belt 23 which is the exact width of the feeder is provided with a plurality 85 of short spikes or pins 24 to receive and rake the burs from the ribs and cause them to move down partition 12' into the huller breast 25 of the gin stand with which the upper compartment is arranged in communication, the upper end of the upper compartment being incidentally arranged in communication with the outlet of the feeder 10.

90 It will thus be seen that with this attachment the cotton will be completely separated from the burs as it passes through the regular gin stand feeder to the gin stand and that the cotton thus cleaned will be fed direct into the cotton roll so that 100 the burs are separated and are disposed of in the same manner as with the regular double breast gin stand.

With this attachment by the aid of the suction all small locks of cotton are saved 105 and ginned and by separating the larger percentage of the cotton fiber from the burs at this operation, the operator can maintain

a full roll of cotton in the stand and save a greater percentage of the lint and seed.

What I claim as new is:—

1. The combination with a gin stand feeder and a gin stand, of a casing positioned between the feeder and the stand and having two compartments therein, one of which is arranged in communication with the outlet of the feeder and with the huller breast of the gin stand while the other compartment is arranged in communication with the first compartment and with the top of the cotton roll chamber of the gin stand, and coöperative means arranged in the compartments for separating the cotton from the burs so that the separated burs and cotton will be respectively delivered to the huller breast and the cotton roll chamber of the gin stand.
2. The combination with a gin stand feeder and a gin stand, of a separating attachment disposed between the feeder and the stand including a casing having two compartments therein, one of which is arranged in communication with the huller breast of the gin stand while the other is arranged in communication with the cotton roll chamber of the gin stand, a saw cylinder rotatably mounted in one compartment of the casing, a suction device connected to one end of the casing the suction of which removes the cotton from the cylinder, a perforated plate arranged in front of the suction device for preventing the passage of cotton therethrough, coöperative means mounted in the casing and interposed between the plate and the cylinder for directing the action of the suction to the top of the cylinder and for removing cotton from the plate and directing it to the cotton roll chamber of the gin stand feeder, and an endless conveyer for coöperating with the saw cylinder for carrying burs away from the cylinder and directing them into the huller breast of the gin stand.
3. The combination with a gin stand feeder and a gin stand, of a casing arranged between the feeder and the stand and provided with two compartments one of which communicates with the huller breast of the gin stand while the other communicates with the cotton roll chamber of the gin stand, an endless conveyer mounted in the top compartment of the chamber for directing burs into the huller breast of the gin stand, a saw toothed cylinder rotatably mounted in the other of the compartments of the casing for engaging and separating cotton from the burs, a pipe extending from one end of the casing and through which there is a suction action for removing cotton from the cylinder, a perforated plate arranged in front of the pipe for preventing the passage of cotton therethrough, a shield mounted in the casing beneath the cylinder for preventing a suction action on the under surface of the cylinder, a coöperating roller arranged between the plate and the cylinder for directing the suction action to the top of the cylinder and for removing cotton from the perforated plate and directing it into the cotton roll chamber of the gin stand.
4. The combination with a gin stand cleaner feeder and a gin stand, of a casing arranged therebetween, a partition providing two compartments in the casing the upper of which communicates with the cleaner feeder and the huller breast of the gin stand while the lower compartment communicates with the cotton roll chamber of the gin stand, the partition being provided with an opening for establishing communication between the two compartments, ribs arranged across the opening, a saw toothed cylinder rotatably mounted in the lower compartment of the casing and having the teeth thereof projecting between the ribs into the upper compartment for engaging cotton which passes down the partition, a pipe extending from one end of the casing and through which there is a suction action for removing cotton from the cylinder, an arcuate shield extending through the partition and arranged beneath the toothed cylinder, means for preventing the passage of clean cotton through the pipe, means for directing the action of the suction to the top of the cylinder and for directing clean cotton into the cotton roll chamber of the gin stand, and conveying means mounted in the upper compartment of the casing for coöperating with the saw toothed cylinder and for carrying burs down the partition so that they may be deposited in the huller breast of the gin stand.
5. The combination with a cleaner feeder and a gin stand, of an attachment arranged therebetween including a casing, a partition providing two compartments in the casing the upper of which communicates with the feeder and with the huller breast of the gin stand while the lower compartment communicates with the cotton roll chamber of the gin stand, the partition being also provided with an opening establishing communication between the two compartments, ribs arranged across the opening, a toothed cylinder rotatably mounted in the lower compartment of the casing and having the teeth thereof projecting between the ribs into the upper compartment for separating cotton from the burs, a pipe extending from the casing and through which there is a suction action, a perforated plate arranged in front of the pipe for preventing the passage of cotton through the pipe, an arcuate shield connected to the partition and arranged between the toothed cylinder for preventing a suction action on the under surface of the cylinder, a roller rotatably mounted in the

casing between the plate and the toothed cylinder, a plurality of flexible flaps arranged on the periphery of the roller for directing the action of the suction on the top of the cylinder and for removing cleaned cotton from the plate and directing it into the cotton roll chamber of the gin stand, and an endless conveyer mounted in the

other compartment of the casing for coöperating with the saw toothed cylinder for moving burs away from the cylinder so that they may be fed into the huller breast of the gin stand.

In testimony whereof I affix my signature.

ED L. HUNTSMAN.
